UNITED STATES PATENT OFFICE.

EDWARD V. HARTFORD, OF NEW YORK, N. Y.

ANTIVIBRATION DEVICE FOR USE ON WHEELED VEHICLES.

1,095,571.

Specification of Letters Patent.

Patented May 5, 1914.

Application filed February 23, 1907. Serial No. 358,814.

To all whom it may concern:

Be it known that I, EDWARD V. HARTFORD, a citizen of the United States, residing in the city, county, and State of New York, have invented certain new and useful Improvements in Antivibration Devices for Use on Wheeled Vehicles, of which the following is a full, clear, and exact specification.

- 10 My invention relates to anti-vibration devices for use on wheeled vehicles employing suspension springs between the body and the running gear for the purpose of retarding the reaction of such springs when they are suddenly compressed or expanded by the passage of the vehicle over inequalities in the surface of the road, and which thereby prevent the shocks and jolts that the vehicle body would otherwise be subject to. In the 20 use of such vehicles on ordinary roads the anti-vibration device may be adjusted to exert a certain retarding effect upon the reaction of the vehicle springs, which is sufficient for the usual inequalities of the road. 25 It occasionally happens, however, that an unusually rough stretch of road is encountered, or a sudden, severe inequality of the road may be met with, which will require a much greater retarding effect upon the springs to prevent the shock to the vehicle body following the reaction of the springs. 30 The object of my invention is to enable the driver or chauffeur of such vehicle, without leaving his seat or stopping the vehicle, 35 to control and regulate the resistance presented by the anti-vibration device to the action of the springs, whereby, in case such unusually rough stretch of road is encountered, or a severe inequality of the road is 40 suddenly met with, he may at once increase such resistance so that the same will be effectual to retard the unusual action or reaction of the springs, which would otherwise follow the passage over such roughness or 45 obstruction, and whereby, after the same has been passed, the anti-vibration device may, if desired, be as readily restored to its normal condition, whereby it presents a proper resistance to the reaction of the springs to 50 the ordinary inequalities of the road.

My invention consists in providing such anti-vibration device with means whereby the resistance to the reaction of the springs may be increased or diminished at will, and 5 in connecting such adjusting means with a

suitable controlling device adjacent to and under the control of the driver or chauffeur, and it also consists of other combinations and details hereinafter more fully pointed out and illustrated in the accompanying drawings, wherein—

Figure 1 is a side elevation of a vehicle containing my invention, parts of the vehicle being omitted for clearness of illustration; Fig. 2 is a detail side view of the anti-vibration device and part of the controlling device; Fig. 3 is an end view of the same, partly in section; Fig. 4 is a plan view of the device applied to a vehicle, parts of which are omitted; and Fig. 5 is a sectional view of the body of the anti-vibration device showing the manner of assembling and attaching the parts.

In the drawings I have illustrated my invention attached to an automobile, to which it is particularly applicable. It may, however, be applied to other wheeled vehicles as well.

The body 1 of the vehicle is suspended through side bars 2, upon springs 3, which are here shown as semi-elliptic. These springs are held upon axles 4 by means of strap bolts 5, which pass over plate 6 upon the spring, and the lower ends of which pass through connecting plate 7, under axle 4, in which position they are held by nuts 8 tapped on their lower ends, and screwing up against connecting plate 7. Wheels 44 are carried as usual by axles 4. Projecting upwardly from the upper surface of plate 6 is a lug 9, upon which is pivotally mounted an upright link or connecting arm 10 by headed bolt 11, so as to swing thereon. Pivotally attached to link 10 by headed bolt 12 is arm 13, which at its opposite end is bifurcated, forming two semi-circular friction bands 14, 15, which terminate in horizontal lugs or ears 16, 17. Friction bands 14, 15, are arranged peripherally with respect to the body or resistance-creating portion of the anti-vibration device, and are in immediate contact with a strap or band 18 of friction material, such as leather, vulcanized fiber, etc., which is mounted peripherally upon the floor of a rectangular channel formed in the periphery of friction disk 19, by the integral annular flange 20, and the outer edge of circular face plate 21.

After the parts 18, 14, and 15 have been inserted in place, the body portion is assem-

bled and attached by headed bolts 22, which pass through holes in friction disk 19 and side frames 2, which is usually faced with channel iron 23 as illustrated, and are secured and held in place by nuts 24, tapped on their inner ends.

The devices for controlling the anti-vibration device are as follows: Lugs or ears 16, 17 are formed with notches 25, 26, upon each side of which are received the sides of an approximately U-shaped strap or buckle 27, through a tapped opening in the bottom of which passes a threaded bolt 28, the inner end of which engages the under side of lug 17, and provides an adjustment for buckle 27. The sides of buckle 27 are connected at their upper ends by a pin or rivet 29, upon which is mounted a cam 30, so as to rotate thereon. This cam is formed upon the end 20 of cam arm 31, which is pivotally connected at 32 to a connecting rod 33, the forward end of which is pivotally connected at 34 to an upright hand lever 35, which at its lower end is fixed upon shaft 36, held in place by 25 straps 37 secured to the under side of side bars 2. Hand lever 35 may be held in any position to which it may be adjusted by any suitable locking device, as, for instance, by pawl 38, which engages the teeth of segmental rack 39, and is controlled by handle 40, to which it is connected by connecting rod 41. The pawl 38 is spring-pressed against the teeth of rack 39 in well known manner. Shaft 36 extends to the opposite side of the 35 vehicle, where it is connected by arm 42 to a set of devices the duplicates of those already described.

I have shown one mode of carrying my invention into effect, but other modes may 40 be employed, as my invention does not reside in the particular mode illustrated by me of controlling the adjustment upon the anti-vibration device, nor in the particular mode of adjusting the same, nor in other details 45 described, and I desire to be understood that other equivalent means may be employed to perform these functions.

It will be understood, of course, that the device of the present invention can be employed to throw the anti-vibration device 50 almost entirely out of operation, so that very little, if any, retarding action will be exercised upon the springs in passing over comparatively smooth roads.

55 The words "manually-operable," where used in the claims, are intended to designate

means capable of operation without the use of a monkey wrench or similar tool.

What is claimed is:

1. A vehicle having a body, running gear, 60 vehicle springs connecting the body to said running gear, rotating frictional retarding devices for the vehicle springs, set screws for adjusting the retarding devices, cams for adjusting the retarding devices, a lever 65 mounted on the vehicle body, and connections between the lever and cams for readily operating the cams from the vehicle body.

2. In combination with a vehicle having a body, running gear, and suspension means interposed between said body and said running gear, an anti-vibration device comprising a member rigidly secured to said body and provided with a friction surface, a bifurcated member movably mounted on said fixed member and having a link connection with said suspension means, said bifurcated member being in constant frictional engagement with said frictional surface on said rigid member, means carried by said bifurcated member to adjust the frictional resistance between said movable and said fixed members to a predetermined degree to retard the relative movement of said running gear and said body under certain conditions, 85 and manually operated means connected to said body and to said bifurcated member and operable independently of said adjusting means for varying the frictional resistance between said fixed and said bifurcated members, to minimize the violent oscillatory movements of said body and said running gear under conditions beyond the effective influence of said adjusting means.

3. In combination with a vehicle having a body, running gear and suspension means interposed between said body and said running gear, an anti-vibration device having a split friction member provided with lugs, a yoke engaging said lugs, an adjusting bolt 100 extending through said yoke and engaging one of said lugs, a cam journaled in said yoke and engaging the other of said lugs, and means for operating the cam.

In testimony whereof I have hereunto set 105 my hand in the presence of my subscribing witnesses.

ELIWHARD L. FARNORD.
